(57) **CLAIM**

The ornamental design for a utensil handle, as shown and
described.

DESCRIPTION

FIG. 1 is a front perspective view of a utensil handle in
accordance with the present design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a front perspective view thereof, shown in an
alternate environmental use.

The broken lines forming the blade in FIG. 7 are for the
purpose of illustrating environment and form no part of the
claimed design. The dot-dash broken lines in all figures
shown immediately adjacent to the claimed areas represent
the boundaries of the design and form no part thereof. None
of the broken lines shown in the drawings form any part of
the claimed design.
